UNITED STATES PATENT OFFICE.

CHARLES W. T. DAVIES, OF NEW YORK, N. Y.

BUTTONHOLE FOR ARTICLES OF WEARING-APPAREL.

1,102,881.

Specification of Letters Patent. Patented July 7, 1914.

Application filed September 10, 1913. Serial No. 789,085.

To all whom it may concern:

Be it known that I, CHARLES W. T. DAVIES, a subject of the King of Great Britain, residing at New York, county of New York, and State of New York, have invented certain new and useful Improvements in Buttonholes for Articles of Wearing-Apparel, of which the following is a specification.

10 This invention relates to buttonholes for articles of wearing apparel and particularly for cuffs.

The ordinary coinciding buttonholes used on soft fabrics such as unstarched cotton or 15 linen, or flannel or silk, especially on folding cuffs of soft material, are not adapted to securely hold and retain studs, links, or other fasteners. It has been proposed in certain earlier devices, not of my own invention, to provide a cuff with free members, 20 flaps, or tabs having a buttonhole and adapted to fold across and overlie another buttonhole, transversely, substantially centrally thereof. In an application filed Feb. 21, 1913, 25 Ser. No. 749,832, I have shown an article of apparel provided with buttonholes arranged in crossed relation to each other but the parts having such buttonholes are not freely folding parts and, on the contrary 30 are permanently secured in overlying relation.

The object of the present invention is the provision of improvements in buttonholes, particularly in connection with soft folding 35 cuffs of any material, whereby accidental loosening or detachment of the stud, link, or other fastener is prevented. This is accomplished by arranging the buttonholes of the respective folds of the cuff in an improved 40 manner and relation, that is to say, with one buttonhole crossing or overlapping the terminus of the other buttonhole and, preferably, that terminus closest to the outer edge of the cuff, whose parts are adapted to 45 fold, as distinguished from one whose parts are permanently relatively fixed in overlying relation.

One of the advantages gained by the present improvements is that the hold on the 50 stud, link, or fastener is very much stronger than is the case where the buttonholes cross or overlap each other intermediate their termini, as only one edge of the vertical buttonhole can spread laterally over the 55 other or horizontal buttonhole, its other edge spreading, if at all, beneath the imperforate

part of the fabric but giving no chance of egress to the head of the stud, whereas if the vertical buttonhole were to cross the horizontal buttonhole near the center, both of its lateral edges would, especially in soft fabrics, if they spread, provide an enlarged hole within the limits and behind the horizontal buttonhole. Furthermore, the fact that the vertical buttonhole is made close to the edge of the cuff, tends very much to limit its spreading laterally on that side next to the outer edge of the cuff due to the shortness of the distance therefrom and the strong stitching at the edges, preventing elasticity as compared with the several inches of cuff between the other margin of the buttonhole and the far edge of the cuff, measured lengthwise of the cuff.

With the present invention there can never exist an empty gap extending all the way through the cuff or other article back of the outer buttonhole, as is the case with the ordinary coinciding buttonholes. In the present arrangement of buttonholes, the fabric of the inner fold of the cuff, and not the buttonhole of the inner fold, comes back of the unoccupied space in the outer buttonhole. The present invention permits the use of a stud, link, or fastener having either 85 a rigid or a flexible connecting shank and heads of minimum size, thus presenting a very easily inserted stud and one which has a neat appearance.

Certain forms of the invention are set forth hereinafter but are not to be considered as excluding its embodiment in other modifications within the spirit and scope of the invention.

In the accompanying drawings: Figure 1, 95 is a face view of a soft folding cuff spread out flat, provided with the present invention; Fig. 2, a side view of the cuff, folded and with the buttonholes arranged for reception of the stud, link, or fastener; Fig. 3, 100 a view like Fig. 2, showing the stud, link, or fastener in position; and Fig. 4, a view like Fig. 1, showing a modification.

Referring first to Fig. 1, the inner and outer parts or folds of the cuff appear at 105 1 and 2, respectively, and the shirt sleeve at 3. Preferably the horizontal buttonholes 4 are provided in the outer fold 2 and the vertical buttonholes 5 in the inner fold 1, but this arrangement may be reversed.

As shown, more particularly by Figs. 2 110 and 3, the relative arrangement of the but-

tonholes 4 and 5 at each end of the cuff is such that they overlap or cross substantially at the terminus of one of them, preferably the terminus of the horizontal buttonhole, 5 when the folds 1 and 2 of the cuff are in overlying relation. The point of overlapping, crossing or intersection 6, Fig. 2, is where the shank, whether rigid or flexible, of the stud 7, Fig. 2, passes through.

10 With the buttonholes arranged as set forth, only one edge of the buttonhole 5 can spread laterally over the length of the horizontal buttonhole 4. Its edge nearest the edge 8 of the cuff, if it spreads at all, 15 spreads beneath an imperforate part, 9, of the fabric of the fold 2. Consequently, the present improved arrangement holds the stud better and more securely than would be the case were the buttonholes to overlap 20 or intersect each other intermediate the ends of the horizontal buttonhole, especially in soft fabrics, as previously set forth. Similarly, the fabric of the inner fold 1 coming opposite the unoccupied part of the buttonhole 4, a greater hold is obtained against movement of the stud inwardly of the buttonhole 4 than would be the case if the buttonholes crossed centrally.

In the modification shown in Fig. 4, the 30 buttonhole 10 of the inner fold 1 is arranged horizontally, instead of vertically and its outer end or terminus 11 is so disposed that it is adapted to cross, intersect, or overlap the inner end 12 of the buttonhole 4 when the fold 2 overlies the fold 1. The same holding effect is obtained with this form of the invention as with that shown in Figs. 1 to 3.

A very great advantage inhering in the 40 form shown in Figs. 1, 2 and 3 is that the upper edge of the cuff when folded, may be adjustably changed to the extent of the length of the vertical buttonhole 5, without removing the cuff links or in the slightest degree disturbing the efficiency of the coöperative hold of the buttonholes on said cuff links, merely by changing (by folding) the relation of the horizontal buttonhole to

the vertical buttonhole from its lower terminal to its upper terminal. Thus, an exposed edge of the cuff, when soiled, may be rolled over and turned in on the wrist side, presenting a new and unsoiled upper edge, while the links are in the cuff and without reversing the folds. This result cannot be obtained when the buttonholes coincide when they are securely fixed in overlying relation, as in my co-pending application, Serial No. 749832.

I do not limit myself to the precise embodiments of the invention shown in the drawings as any other forms which will accomplish the same result by substantially similar means, are within the spirit and scope of the invention.

Having thus described my invention, what I claim as new and desire to secure by Letters Patent, is:

1. A double folding cuff, the relatively foldable parts or folds of which are provided with link-holding buttonholes intermediate their upper and lower edges which are arranged so that only a substantially terminal portion of one buttonhole overlaps a portion of the other buttonhole when the 75 folds are in overlying relation.

2. A soft, double, folding cuff having separate, single buttonholes, each extending right through the body of the cuff in the upper and lower folds thereof adjacent its outer and intermediate of its upper and lower edges, said buttonholes being so arranged in relation to each other that when the two folds of said cuff are in overlying relation one of said buttonholes transversely overlaps both sides of, and lies in direct juxtaposition to, the other buttonhole at only a substantially terminal point of the last-named buttonhole.

In testimony whereof, I hereunto affix my 90 signature in presence of two witnesses.

CHARLES W. T. DAVIES.
